WILLIAM SPACKE, OF INDIANAPOLIS, INDIANA, ASSIGNOR TO THE F. W. SPACKE MACHINE COMPANY, OF INDIANAPOLIS, INDIANA, A CORPORATION OF INDIANA.

INLET-VALVE FOR INTERNAL-COMBUSTION ENGINES.

1,108,266.

Specification of Letters Patent. Patented Aug. 25, 1914.

Application filed January 28, 1914. Serial No. 815,078.

To all whom it may concern:

Be it known that I, WILLIAM SPACKE, a citizen of the United States, residing at Indianapolis, in the county of Marion and State of Indiana, have invented a new and useful Inlet-Valve for Internal-Combustion Engines, of which the following is a specification.

The object of my invention is to produce an effective means for supporting the inlet valve casing of an internal combustion engine in such manner that the inlet valve may be readily accessible.

The accompanying drawings illustrate my invention.

Figure 1 is a fragmentary axial section practically full-size of an engine embodying my invention; Fig. 2 a side elevation in partial vertical section at right angles to the plane of Fig. 1; Fig. 3 a plan of the parts shown in Fig. 2; and Fig. 4 a perspective of one of the fastening hooks.

In the drawings, 10 indicates the main body of the engine provided with a passage 11 which, at its inlet end, is provided with an outwardly presented shelf 12 flanked by a threaded opening 14. Dropped into the opening 14 and seating upon the shelf 12 is a valve ring 15 provided with a central sleeve 16 which forms the support for the stem 17 of the valve 18 seated in the inner end of ring 15. Surrounding sleeve 17 is a spring 19 which acts upon stem 17 to normally close the same. Threaded into the opening 14 is a valve-ring clamping member 21 which serves to clamp the valve ring 15 in place. This ring 21 is formed upon its outer end to receive a packing gasket 22 which lies between it and the open lower end of an inlet casing 23. Within the casing 23 the clamping ring 21 is provided with a plurality of axially projecting lugs 24 by means of which the clamping ring may be readily tightened and loosened. Clamping ring 21 is provided with an inwardly projecting and undercut flange 25 beneath which may be projected arc-shaped hooks 26 carried by the lower end of a pair of clamping bolts 27, the threaded shanks of which are projected through openings 28 in casing 23 and adapted to receive nuts 29.

The inlet casing 23 is provided in its upper part with a chamber 31, the open upper end of which is covered by a readily removable cap 32 conveniently held in place by a

spring finger 33. Projected upwardly into chamber 31, through a bushing 34, is the valve stem 17 and pivotally mounted within chamber 31 is a valve operating lever 35 one end of which engages the stem 17 and the other end of which is provided with a downwardly presented cup 36 arranged in alignment with the bore of a boss 37 extending through the inlet passage leading into the main chamber of the casing 23, the arrangement being such that a valve-operating rod 38, projected upwardly through the bore of boss 37, may enter the cup 36 of lever 25.

For convenience in priming the engine, I provide the casing 23 at an easily accessible point with a priming opening 40 normally covered by a swinging cover plate 41 provided with a convenient thumb piece 42.

In use, the valve ring 15 with its valve is dropped into place upon shelf 12 and ring 21 is then screwed firmly to place so as to hold the ring 15 in proper position. Thereupon casing 23 is placed upon gasket 25 and the bolts 27 are passed downwardly through the opening 28, the hooked ends being first swung inwardly so as to pass beyond the undercut lower edge of flange 25 and then being swung outwardly so as to bring the hooks 26 beneath the flange. Thereupon the nuts 29 are screwed down so as to draw the hooks 26 upwardly beneath flange 25 and drive the nuts downwardly upon casing 23 so as to firmly hold it in place. At any time that the valve needs adjustment or inspection, nuts 29 may be readily loosened and bolts 27 withdrawn or swung inwardly whereupon casing 23 may be lifted from place without the necessity of any separation or adjustment of the connection between the operating rod 38 and the valve, the downwardly presented cup 36 withdrawing freely from the upper end of rod 38.

I claim as my invention:

1. The combination with an engine and a valve therefor, of a clamping ring for said valve provided with an inwardly projected flange, a casing member arranged to cover the valve, and a casing clamp comprising a hook-shaped member projected through the casing member and engaging the inwardly projected flange of the clamping ring said hook-shaped member having a threaded outer end and a nut threaded thereon and engaging the casing.

2. The combination with an engine and a valve therefor, of a clamping ring for said valve provided with an inwardly projected flange, a casing member arranged to cover the valve, and a casing clamp comprising a hook-shaped member projected through the casing member and engaging the inwardly projected flange of the clamping ring. 5
3. The combination with an engine having a valve opening, of a valve associated with said opening, a casing surrounding said opening, and clamping means for said casing, said clamping means comprising a bolt having a hook-shaped inner end projected through the casing and engaging with a portion carried by the engine within the casing. 10
4. The combination with an engine having a valve opening, of a valve associated therewith, a casing encompassing said valve, a valve-operating member, an intermediate connection, carried by the casing, operatively connecting the valve operating member and the valve and engaging the valve operating member in one direction only, and means 15 for clamping the casing in position said means comprising a hook-shaped member projected through the casing and engaging with a portion within the casing. 20
5. The combination with an engine having a valve opening, of a valve associated therewith, a casing encompassing said valve and removable independently of the valve, a valve-operating member, an intermediate connection, carried by and within the casing, operatively connecting the valve operating member and the valve and engaging the valve operating member in one direction only, and means for clamping the casing in position. 25
- 40 6. The combination with an engine having a valve opening, of a valve associated therewith, a clamping ring threaded into said opening and clamping the valve in place, said clamping ring having an inwardly projecting flange, a casing encompassing said valve, a hook projected through the casing into engagement with the flange of the clamping ring, a nut mounted on the outer end of the hook and engaging the casing to clamp it in place, a valve-operating lever mounted in the casing and engaging the valve in one direction, and a valve operating member projected into the casing and engaging the valve operating lever in one direction. 50
7. The combination with an engine having a valve opening, of a valve associated therewith, a clamping ring threaded into said opening and clamping the valve in place, said clamping ring having an inwardly projecting flange, a casing encompassing said valve, a hook projected through the casing into engagement with the flange of the clamping ring, and a nut mounted on the outer end of the hook and engaging the casing to clamp it in place. 60
8. The combination of an engine having a valve opening, a valve ring mounted therein, a valve associated with and carried by said valve ring, a casing removably mounted on said engine and into which the valve stem projects, a valve-operating member also projecting into said casing, an intermediate connection carried by and within the casing and operatively connecting the valve-operating member and the valve stem, and means for clamping the casing in position, said means when released permitting the casing and intermediate connection to be removed while leaving the valve-operating member 70 and valve in place. 75
- In witness whereof, I have hereunto set my hand at Indianapolis, Indiana, this twenty-sixth day of January, A. D. one thousand nine hundred and fourteen.
- WILLIAM SPACKE.
